UNITED STATES PATENT OFFICE.

KONRAD SCHAFFLER, REKTE GLÖSSL, OF VIENNA, AUSTRIA-HUNGARY.

DYNAMO-ELECTRIC APPARATUS FOR FIRING MINES.

1,072,511.

specification of Letters Patent.

Patented Sept. 9, 1913.

Application filed February 4, 1913. Serial No. 746,200.

To all whom it may concern:

Be it known that I, KONRAD SCHAFFLER, REKTE GLÖSSL, residing at Vienna, Austria-Hungary, subject of the Emperor of Austria-Hungary, have invented certain new and useful Improvements in Dynamo-Electric Apparatus for Firing Mines; and I do hereby declare the following to be a full, clear, and exact description of the invention, such as will enable others skilled in the art to which it appertains to make and use the same, reference being had to the accompanying drawings, and to letters or figures of reference marked thereon, which 10 form a part of this specification.

This invention relates to a spring actuated electrical apparatus for firing mines, the source of current of which apparatus is constituted either by a dynamo machine or 20 by a magnetic inductor. In similar mine firing apparatus the winding up of the actuating spring is performed by means of a key, a crank or the link; the mechanism comprising a pawl which engages a ratchet 25 wheel provided in the transmission gear, locks this gear and prevents the release of the actuating spring. The starting of the firing apparatus is performed by disengaging the pawl from the said ratchet wheel. 30 If now the pawl should be raised out of engagement with the ratchet wheel and consequently the current generator put in operation before the actuating spring has been completely or sufficiently wound up, the current 35 which will be caused to flow through the firing circuit connected to the firing device will be too weak, and consequently the igniters comprised in the firing circuit will not be brought to explosion or only some of 40 them will explode.

The present invention has for its purpose to provide an improved arrangement of the apparatus for firing mines of the kind above referred to, and the improvement essentially consists in means whereby the apparatus can only be operated to generate the current when the actuating spring is completely wound up. According to the invention this is obtained in such a manner 45 that the raising of the above mentioned pawl out of engagement with the ratchet of the driving wheel, which is performed by means of a hand operated key, lever or the like, can take place only when the actuating spring is completely wound up, so that 50 the sending of too weak a current into the

firing circuit and consequently missfires are absolutely prevented. The means provided for preventing the premature disengagement of the pawl prevent at the same time 60 the reengagement of the pawl in the ratchet during the running out of the actuating spring, so that the released spring cannot be interrupted.

The object of the invention is represented 65 by way of an example in the accompanying drawings in which—

Figure 1 shows a front elevation of the firing apparatus with the front plate removed. Fig. 2 represents a side elevation 70 of the driving gear of the apparatus. Figs. 3 and 4 are detail side and end views of the locking and releasing organs.

The armature *a* of the dynamo is actuated by a pinion *c* keyed on the shaft *b* of 75 the armature said pinion meshing with a toothed wheel *d* that forms the casing or barrel of the driving spring *f*. The spring *f* has one end affixed to the wall of the casing, and the other end fastened to the shaft *e* 80 of the toothed wheel *d*, and is under preliminary tension; after a full revolution of the toothed wheel *d* in the direction of the arrow I the said spring is completely wound up and is standing under full tension. The 85 toothed wheel *d* is provided with a nose *g* which during the rearward rotation of the toothed wheel *d* corresponding to the unwinding of the spring *f* comes into contact with an abutment *i* affixed to the frame *h* 90 of the apparatus in the path of the nose and has for its purpose to limit the rearward rotation of the spring barrel and thus to prevent the complete unwinding of the spring *f*. In order to prevent a violent 95 shock by the recoil of the spring barrel this abutment *i* consists of a strong spring. An arc-shaped recess *g'* (Fig. 1) is formed in the frame of the apparatus in the vicinity 100 of the spring or abutment *i* and permits this spring *i* to bend under the action of the nose *g* striking against the same. The winding up of the main spring *f* is performed by a pinion *j* meshing with the toothed wheel *d* and keyed upon the winding-up shaft *k*, this latter being provided 105 with catching pins. The toothed wheel *d* carries a ratchet ring *l* and a projecting ring *m* which is arranged between the toothed wheel *d* and the ratchet ring *l* and 110 may be of a somewhat greater diameter than the ratchet ring *l*.

In the frame *h* of the apparatus is pivoted a shaft *o* that can be rotated by means of a key or of a lever or the like and upon this shaft *o* is loosely mounted a pawl *n* which is kept in engagement with the ratchet ring *l* by means of a spring *p*. On the shaft *o* is furthermore fixed a ring *q* provided with a shoulder *r*. This shoulder is of such a length that when the ring *q* is rotated in the direction of the arrow II (Fig. 1) the end of this shoulder *r* abuts against the projecting ring *m* and thus prevents a further rotation of the ring *q*. The shoulder *r* of the ring *q* is provided with a lateral projection *s* reaching between two abutments *n*¹, *n*², provided on the pawl *n*. A spring *t* always tends to rotate the ring *q* in such a manner as to make the projection *s* bear against the abutment *n*¹ of the pawl *n*.

The ring *m* is provided in its periphery with a recessed portion *u* which lies opposite the ring *q* and the pawl *n* when the main spring *f* is either completely wound up or completely unwound. This recessed portion is sufficiently deep to permit the shoulder *r* of the ring *q* to be swung by the rotation of the shaft *o* in the direction of the arrow II.

In the position of the driving members shown in Fig. 1 the main spring *f* is unwound, and these members take more or less the same position when they are under full tension. In either case the pawl *n* can be brought out of engagement with the ratchet *l* by turning the shaft *o* which rotates the ring *q* in the direction of the arrow II against the action of the spring *t* until the lateral projection *s* of the shoulder *r* bears against the abutment *n*² of the pawl *n*, and overcoming the pressure of the spring *p* pushes the pawl *n* in its position shown in dash and dot lines. During this motion the shoulder *r* has passed the recessed portion of the ring *m* and has occupied the position shown in dash and dot lines. When the spring *f* has been put under tension and released the toothed wheel *d* rotates backward for nearly a full revolution. Directly at the beginning of this rearward rotation the recessed portion *u* of the ring *m* passes the releasing members *n*, *r* and the full, non-recessed part of the ring then engages the shoulder *r* of the ring *q* which is in its position shown in dash and dot lines. In this manner the projecting ring *m* prevents the ring *q* from returning into its position shown in full lines under the action of the spring *t* during the rearward rotation of the toothed wheel *d* when the key, lever or like part which actuates the shaft *o* should be accidentally released. In this manner the pawl *n* is prevented from coming again into engagement with the ratchet *l* during the rearward rotation of the latter. Only after a nearly full

revolution of the toothed wheel *d*, when the recessed portion *u* of the ring *m* again comes opposite the shoulder *r*, can the ring *q* and the pawl *n* return back again into their respective positions shown in full lines under the action of the springs *t* and *p* respectively.

When the main spring *f* is being wound up, by the rotation of the toothed wheel *d* in the direction of the arrow I, the recessed portion *u* of the ring *m* passes the shoulder *r* of the ring *q* at the beginning of the movement. The projecting ring *m* prevents the ring *q* with its shoulder *r* from being brought into the position shown in dash and dot lines, and prevents also the pawl *n* from being raised out of engagement with the ratchet *l*, until after nearly a full revolution of the toothed wheel *d* and the main spring *f* is completely wound up, so as to be under full tension, and the recessed portion *u* of the ring *m* is again passing the shoulder *r*. If the main spring *f* be released and should put the dynamo-machine in operation before this main spring is completely wound up, it would result in sending currents of insufficient strength into the igniting circuit and consequently a misfiring of the igniter. The same conditions would occur when the pawl *n* was brought into engagement with the ratchet *l* before the spring *f* has been completely unwound. Now, the improved apparatus hereinbefore described absolutely and securely prevents a premature release of the main spring and also a premature re-engagement of the pawl in the ratchet during the release of the main spring.

The entire mine firing apparatus is arranged within a closing casing in such a manner that only the ends of the shafts *k* and *o* extend out of the casing.

I claim.

1. In a dynamo-electric firing apparatus, a spring for rotating the armature of the apparatus, means to put the spring under tension, and means to prevent the release of the tensioning means before the spring is under full tension.

2. In a dynamo-electric firing apparatus, a spring for rotating the armature of the apparatus, a ratchet wheel adapted to put the spring under tension, a pawl to engage the ratchet wheel, a pawl actuating member, and means to prevent the operating of the latter during the winding and unwinding of the spring.

3. In a dynamo-electric firing apparatus, a spring for rotating the armature of the apparatus, a ratchet wheel to tension the spring, a pawl to engage the ratchet, means to move the pawl out of engagement with the ratchet, and means to prevent the operation of said moving means during the unwinding of the spring.

4. In a dynamo-electric firing apparatus, a spring for rotating the armature of the apparatus, a ratchet connected with the spring, a barrel to rotate the ratchet to put the spring under tension, a pawl adapted to engage the ratchet, means to move the pawl out of such engagement, and means on the barrel to lock the pawl moving means during the winding and unwinding 10 of the spring.
5. In a dynamo-electric firing apparatus, a spring for rotating the armature of the apparatus, a barrel inclosing the spring, a ratchet on the barrel, a pawl adapted to engage the ratchet, a rotatable member adapted to engage the pawl and move the latter away from the ratchet, and a ring on the spring barrel adapted to lock the rotatable member in engagement with the pawl during 15 the unwinding of the spring.
6. In a dynamo-electric firing apparatus, a spring for rotating the armature of the apparatus, a barrel to wind the spring, a ratchet on the barrel, a swinging pawl movable into engagement with the ratchet, a rotatable actuating member to engage the pawl and move the latter away from the 20
- 25
- 30
- 35
- 40
- 45
- ratchet, a ring on the spring barrel adapted to engage the actuating member and lock the latter against rotation during the unwinding of the spring, said ring having a recess to release the actuating member and permit the pawl to swing into engagement with the ratchet during the winding of the spring.
7. In a dynamo-electric firing apparatus, a spring for rotating the armature of the apparatus, a ratchet connected with the spring, a drum to rotate the ratchet, a pawl to engage the ratchet, a pawl actuating member, means to prevent the operation of the latter during the winding and unwinding of the spring, an abutment on the barrel, and a spring mounted in the path of the abutment to engage the latter and thereby limit the rotation of the barrel.

In testimony that I claim the foregoing as my invention, I have signed my name in presence of two subscribing witnesses.
